SHARPENING JIG

Raymond L. Keith, De Land, Fla.

Application August 6, 1937, Serial No. 157,794

2 Claims. (Cl. 51—158)

This invention is a sharpening jig and has as its object the provision of a device of this character particularly designed for sharpening chisels, bits, and the blades of planes and analogous tools; and the invention together with its objects and advantages will be best understood from the following description taken in connection with the accompanying drawings wherein,

Figure 1 is a side elevational view of the jig,
10 Figure 2 is a top plan of the base of the jig,

Figure 3 is a top plan view of the plate assembly forming part of the jig,

Figure 4 is a perspective view of a blade supporting member,

15 Figure 5 is a perspective view of the upper end of a supporting post.

Referring to the drawings more in detail it will be seen that in the preferred embodiment thereof, the sharpening jig comprises a base plate 5 provided in the top face thereof and adjacent opposite longitudinal edges thereof with longitudinally spaced, continuous grooves 6, 7, elongated longitudinally of the base plate.

Between one pair of grooves, as for example 25 the grooves 6, plate 5 accommodates thereon an oil stone 8 or other suitable abrasive element; plate 5 having struck-up therefrom suitably positioned retaining clips or ears 9 to engage at opposite sides and the respective opposite end edges 30 of the abrasive element 8.

A relatively shorter rectangular plate 10 is supported at one end thereof through the medium of legs or standards 11 and at the relatively opposite end thereof through the medium of legs or 35 standards 12.

The legs or standards 11 are provided in their lower ends with sockets to accommodate balls or other suitable anti-friction elements 13 that ride in the grooves 6. At their upper ends the 40 legs or standards 11 have reduced extensions 14 that extend through openings provided in the corner portions of the plate 10 and are provided with collars 15 that are retained on the extensions 14 against rotative movement, but in a 45 manner to permit longitudinal or vertical movement of the collars on the ends 14 through the medium of pins 16 that are accommodated in slots 17 provided in the ends 14 of the legs or standards 11.

50 Springs 18 are disposed about the reduced ends 14 of the legs or standards 11 and are interposed between the plate 10 and shoulders 19.

Resting flatly on the plate 10 is a smaller plate 20 that is secured at the desired angular adjustment on the plate 10 through the medium of

wing nut equipped bolts 21 rising from the plate 10 and accommodated in arcuate slots 22 provided in plate 20 adjacent to relatively opposite ends of the plate as shown in Figure 3.

Plate 20 is disposed over an opening 23 provided in the plate 10, and is itself equipped with a rectangular opening 24 that accommodates the blade 25 to be sharpened.

Adjacent one end of the opening 24 plate 20 has struck-up therefrom a web 26 through which 10 is threaded a clamping bolt 27 provided with a clamping head 28.

At opposite sides of the opening 24 there are provided integral depending flanges 29 between the lower corners of which is pivoted as at 30 15 a blade supporting plate or member 31.

Plate 31 has hinged to the underside thereof as at 32, a slotted supporting brace 33 that is adapted to rest on the plate 20 and accommodates in the slot thereof a wing nut equipped 20 bolt 34 rising from the plate 20. Obviously through the medium of the brace 33 and wing nut equipped bolt 34 the blade supporting plate 31 may be held in the desired angle of inclination with the blade 25 to be sharpened clamped 25 between the plate 31 and the head 28 of adjusting screw 27, as will be clear from a study of Figure 1.

It will thus be seen that with this device the blade 25 is held at the desired angle of inclination with the edge thereof to be sharpened engaging the top surface of the abrasive block 8.

With the blade thus supported in engagement with abrasive block 8 the carriage 35 consisting of the aforementioned plate 10, plate 20 and associated parts, legs 11, and the legs 12, which latter at their upper ends are riveted to one end of the plate 10 at the corners thereof, and at their lower ends are provided with sockets accommodating balls or anti-friction elements 36 working 40 in the grooves 7, said carriage 35 may be caused to travel back and forth and laterally from one side to the other as controlled by the cooperating grooves 6 and balls 13, and cooperating grooves 7 and balls 36 so that the edge of the blade 25 45 is moved in corresponding direction over the surface of the block 8 to effect a sharpening of the blade edge in a positive, quick and efficient manner. Obviously by adjusting the plate 20 to the desired angle relative to the plate 10 the edge of 50 the blade to be sharpened may be held in the desired oblique angle to the length of the abrasive stone 8 as may be required for a more effective sharpening of the blade edge.

Also springs 18 provide a yielding support for 55

one end of the plate 10 and associated parts whereby pressure of the hand on the plate 10 may be utilized for controlling the amount of pressure with which the edge of the blade 25, being sharpened, will be brought into and maintained in contact with the surface of the abrasive element 8.

It is thought that a clear understanding of the construction, utility and advantages of an invention of this character will be had without a more 10 detailed description.

Having thus described the invention, what is claimed as new is:

1. A blade sharpening jig comprising a base plate provided in the top surface thereof with 15 pairs of opposed, endless elongated grooves, means on said base plate for engaging and securing an abrasive block in position on the base plate, a carriage including a plate, supporting legs for the plate, and anti-friction means on the lower ends 20 of the supporting legs engaging in said grooves for controlling the direction of movement of said carriage relative to said plate and the abrasive element thereon, and a blade holding and clamping device mounted on the plate of said carriage, said blade holding and clamping device 25 including an apertured plate mounted on the carriage plate and provided at one end of said aperture with an upwardly directed flange, a clamping screw threaded through an opening in said flange, said apertured plate also having flanges depending 30 therefrom at opposite sides of the aperture, a blade supporting member pivoted at one end between said flanges, interengaging means on said apertured plate and said blade supporting mem- 35 ber for securing the latter at the desired position of angular adjustment, said blade support-

ing member and said clamping screw cooperating to clamp a blade to be sharpened therebetween.

2. A blade sharpening jig comprising a base plate provided in the top surface thereof with pairs of opposed, endless elongated grooves, means on said base plate for engaging and securing an abrasive block in position on the base plate, a carriage including a plate, supporting legs for the plate, and anti-friction means on the lower ends of the supporting legs engaging in said grooves for controlling the direction of movement of said carriage relative to said plate and the abrasive element thereon, and a blade holding and clamping device 15 including an apertured plate mounted on the carriage plate and provided at one end of said aperture with an upwardly directed flange, a clamping screw threaded through an opening in said flange, said apertured plate also having flanges depending 20 therefrom at opposite sides of the aperture, a blade supporting member pivoted at one end between said flanges, interengaging means on said apertured plate and said blade supporting member for securing the latter at the desired position of angular adjustment, said blade supporting member and said clamping screw cooperating to clamp a blade to be sharpened therebetween, and means resiliently connecting said carriage plate at one end thereof to its supporting legs 25 whereby pressure of the blade to be sharpened against the abrasive element may be regulated at the will of the operator, and means for securing said apertured plate on the carriage plate for angular adjustment relative to the carriage plate. 30
